SYSTEM OF ELECTRICAL DISTRIBUTION.

1,295,498.

Specification of Letters Patent.

Patented Feb. 25, 1919.

Application filed March 9, 1917. Serial No. 153,750.

To all whom it may concern:

Be it known that we, EDWARD M. HEWLETT and CHARLES I. BURKHOLDER, citizens of the United States, residing, respectively, at 5 Schenectady, county of Schenectady, State of New York, and at Charlotte, county of Mecklenburg, State of North Carolina, have invented certain new and useful Improvements in Systems of Electrical Distribution, 10 of which the following is a specification.

Our invention relates to systems of electrical distribution and particularly to controlling means for the circuits of a plurality of electric conductors or feeders of such sys- 15 tems:

When it is desired to open a plurality of feeders in predetermined time intervals, it has been the usual practice to provide each of the protective relays controlling the in- 20 dependent trip circuits for the feeders with separate timing means, whereby their time of operation could be regulated. It has been found, however, that when it is essential that a plurality of feeders be opened in a pre- 25 determined sequence that the independent timing devices cannot be relied upon, as due to one cause or another they often fail to work. According to our invention these difficulties are overcome by using protective re- 30 lays for each trip circuit of the instantaneous type and providing a common device operatively related to each trip circuit for introducing a time interval between the operation of each relay and the completion of 35 its corresponding trip circuit. The operation of any protective relay in response to an abnormal condition on its feeder sets the common timing device into operation and as long as the relay is actuated, the common 40 device is operated until, after a predetermined time, it completes the trip circuit of the relay actuated, to open its corresponding feeder. The time interval between the occurrence of the abnormal condition and the 45 opening of the corresponding feeder is therefore controlled by a device in common to all the trip circuits for the feeders and there is no danger that any feeder will be opened before its time interval and due to 50 the operation of the common timing device the sequence of opening the feeders is al-

ways certain. Means is also provided for at will changing the time interval for tripping each feeder and thereby making the sequence of opening of the feeders anything 55 desired.

The novel features which we believe to be characteristic of our invention will be definitely indicated in the claims appended hereto while the features of construction and 60 mode of operation will be best understood by reference to the following description, taken in connection with the accompanying drawings which show the preferred embodiment of our invention and in which the figures show, diagrammatically, our novel control means with connections controlling the 65 circuits of a plurality of feeders.

In Fig. 1 we have shown our novel and improved control means as comprising a dial 70 switch having a movable contact arm or member 1 coöperating with two sets of fixed contact members 2 and 3, the contact member 1 being mounted for rotative movement on a shaft 4, and the two sets of 75 contact members 2 and 3 being concentrically arranged about the shaft 4 in the path of travel of contact member 1. Concentrically arranged also about the shaft 4 is a contact member or ring 6 to which the 80 contact arm is operatively connected or maintained in engagement by any suitable resilient conducting means. The shaft 4 and the contact arm 1 are actuated or rotated by means of a motor 7 through a mag- 85 netic clutch 8 and worm reduction gearing 9, the reduction gearing being so related to the speed of revolution of the motor that the contact arm engages the sets of contacts 2 and 3 in predetermined successive time in- 90 tervals or periods of time, the contacts 2 being arranged to be engaged just prior to the engagement of the corresponding contacts. The contact arm 1 is biased to initial position by a spring 10.

The two concentric sets of contact members 2 and 3 comprise an equal number of contacts, the inner set of contacts 2 being known as bell contacts and the outer set of contacts 3 as the trip contacts. In Fig. 1 we 100 have shown our timing device as adapted to control the circuits of eleven feeders but we

have shown the connections to our timing device for four of the feeders only, as it is understood that the remaining feeders are similarly connected.

5 Of the eleven feeders controlled by our timing or control device we have shown, as just stated, only four feeders namely 11, 12, 13 and 14, in one line diagram for purpose of clearness, controlled by the automatic circuit opening devices or switches 15, 16, 17 and 18 respectively. For tripping each switch, there is provided the trip coils 19, 20, 21 and 22 respectively which are in independent trip circuits controlled by their 10 respective electroresponsive devices or protective relays 23, 24, 25, 26 respectively, the connections of the relay windings to their respective feeders being omitted for purposes of clearness.

20 It is understood that the protective relays may be responsive to any predetermined abnormal condition on their feeders but, by way of example, we have shown these relays as of the instantaneous over 25 load type. In Fig. 1 we have shown each independent trip circuit corresponding to the feeders as connected to one of the fixed or trip contacts 3 all the trip circuits being thus controlled by the common control 30 means or timing device.

Each trip circuit is also controlled by its respective protective relay, operating to close their contacts 27 and 28 in their respective trip circuit. Each relay, in operating, also engages a third contact 29 which coöperates with contact 27 to control the circuit of the motor 7 and magnetic clutch 8 in parallel. The contacts 27 and 29 for each relay being in parallel and connected 35 to the control buses 30 and 31, it is evident that the actuation of any relay to close its contacts 27 and 29 sets the motor in operation.

Operatively related to the shaft 4 and 45 preferably carried thereon is a cam member 32 which coöperates with a control device for the motor circuit. This control device consists of a switch member 33 normally in engagement with a contact 34 to close the 50 control circuit of the motor 7 but movable by the cam member 32 when the contact arm 1 completes one revolution or reaches the end of its path of movement, to break engagement with contact 34 and open the 55 motor control circuit and to engage contact 35 to close an indicating or alarm circuit. The switch member 33 then remains in position to hold the motor circuit open until reset in motor operating position by 60 hand.

The operation of our control means or timing device may be described as follows: Under normal conditions on each feeder the timing device, protective relays and switches 65 are in the position indicated in Fig. 1. Let

us assume a predetermined abnormal condition, such as an overload, occurs on feeder 12, for instance. Its electroresponsive device or protective relay 24 instantly operates in response to the predetermined condition 70 and moves into contact closing position to close simultaneously, its three contacts 27, 28 and 29. A motor operating or control circuit is then completed from the positive source of current through the switch 36 75 along conductors 37 to switch 33, contact 34, conductor 38, through the clutch 8 and motor 7 in parallel and then by conductor 39 to the control bus 30 and thence by conductor 40 to contacts 29 and 27 of relay 24, 80 now closed by the actuation of the relay, to the control bus 31 and thence by conductor 36^a to the negative source of current. The closing of this circuit by the actuation of the relay 24 sets the motor 7 into operation 85 through its magnetic clutch 8 and the shaft 4 is rotated in the direction of the arrow, tensioning spring 10. It is apparent that as the contacts 27 and 29 of each relay are in parallel that the movement of any of the 90 protective relays to contact closing position will close the motor control circuit and set the timing device into operation. Irrespective of which relay sets the timing device into operation, the contact arm 1 rotates in 95 the direction of the arrow, engaging the corresponding contacts in each concentric set of contacts 2 and 3 corresponding to the feeders.

As the contact arm 1 is actuated, the first 100 movement of the timing device is to cause the contact arm to engage contacts 41 and 42. The trip circuit of feeder 11 is open at its contacts 27 and 28, as normal conditions exist on the feeder 11 and its relay 23 is in 105 normal or contact opening position, consequently nothing happens by the engagement of trip contact 41 but the engagement of the bell contact 42 corresponding to feeder 11 completes an indicating or alarm circuit 110 from the positive source of current, through switch 36 along conductor 45 to contact ring 6, contact arm 1, contact 42, to the indicating device or bell alarm 46, to the control bus 31 and back over conductor 36^a to the 115 negative source of current. Indicating device or bell alarm 46 thereupon operates and gives a signal. The contact arm 1 being still maintained in operation by the motor 7, continues in its path of movement, breaks 120 engagement with contacts 41 and 42 and next engages simultaneously contacts 43 and 44 corresponding to feeder 12. As contacts 42 and 44 and the other contacts in the concentric set of bell contacts 2 are connected in 125 parallel, the engagement of the arm 1 and contact 44 closes the bell alarm circuit again in the manner just described. With the engagement of contact 43, however, the timing device has assumed a circuit closing or 130

contact closing position in the trip circuit corresponding to the faulty feeder 12 whose relay 24 is in contact closing position due to abnormal conditions on its feeder. In 5 this position of the contact arm, the tripping circuit for the feeder is therefore completed from the positive source of current along conductor 45, contact ring 6, contact arm 1, contact 43, trip coil 20, contacts 27 and 28 10 of relay 24, now in contact engaging position, to the control bus 31 and back over conductor 36^a to the negative source of current. The trip circuit for feeder 12 being completed, its trip coil 20 is energized and 15 switch 16 automatically opened to disconnect the feeder.

Upon opening the feeder, its relay 24 is deenergized and contacts 27 and 28 opened and at the same time contact 29 is disengaged which with cooperating contacts 27 20 opens the motor control circuit whereupon the motor 7 is interrupted and its clutch 8 is disconnected. Shaft 4 with contact arm 1 is then rotated in the reverse direction 25 and returns to its initial position under the action of the resetting means or spring 10. It is thus apparent that in response to a predetermined abnormal condition, such as an overload, upon the feeder 12, its relay 30 24 is operated to set in operation the timing device which after a predetermined time corresponding to the time required for the contact arm to move from initial position into position to engage contact 43, 35 the trip circuit for feeder 12 is completed and the feeder opened. In a similar manner our common timing device is adapted to be set into operation in response to the actuation of any of the protective relays 40 and the contact arm 1 thereof carried successively into a circuit closing position in each trip circuit in a definite sequence until the trip circuit is reached whose relay has operated when this trip circuit is closed 45 and its corresponding feeder opened. As the movement of the timing device through its contact arm 1 into circuit closing position in each trip circuit is indicated by the alarm bell, an attendant by knowing 50 the sequence of tripping the feeders, may merely count the number of times the bell strikes to ascertain which feeder is in trouble. It is also understood that any other type of recording device may be used 55 to record the movement of the contact arm 1 from one circuit closing position to the next.

If for any reason the protective relay corresponding to the faulty feeder is not 60 opened when its feeder circuit is opened, the motor control circuit remains closed and the contact arm 1 continues to successively engage the remaining set of contacts. Under such circumstances, when the contact 65 arm completes one revolution or reaches

the limit of its travel, an interrupting means is actuated, the cam member 32 on the shaft 4 reaching a position to engage the control or limit switch 33 and move it from engagement with the contact 34 70 into engagement with the contact 35. This device thereby interrupts the motor control circuit, which circuit cannot again be closed until the control switch 33 is reset by hand. At the same time that the motor control 75 circuit is opened, the contact arm 1 engages the latching means or catch 35^a and is thereby held locked or restrained from returning to its initial position until the catch is released by hand. The engagement 80 of the contact 35 by the switch 33 closes an alarm circuit from the positive source of current along conductor 37, to switch 33, through contact 35, to alarm device 47, and the control bus 31 back to the negative 85 source of current. The alarm 47 rings continuously to notify the operator of the trouble.

From the connections shown in Fig. 1, the trip circuit for each feeder is operatively related to one of the trip contacts 3 so that the trip circuits are closed in a definite sequence and in predetermined successive time intervals. It is often desirable to change the sequence of tripping and to 90 enable each feeder tripping circuit to be closed in various time intervals. In order to adjust the time of tripping, we provide as shown in Fig. 2, means whereby the time interval for tripping each feeder may be 95 varied at will.

In Fig. 2 we have, for purposes of clearness, shown only a portion of our control device of Fig. 1. Between the series of trip contacts 3 and the protective relays 105 corresponding to each feeder we provide a time calibrating or regulating means consisting of a dial switch corresponding to each feeder having rotatably movable contact members or arms 48 cooperating with a 110 series of concentrically arranged fixed contacts 49, the number of fixed contacts 49 corresponding to the number of different time settings. In Fig. 2 we have shown, due to lack of space, the time adjusting or 115 calibrating means applied to but four feeders as in Fig. 1 but it is understood that similar means are provided for each feeder of the plurality controlled. We have also shown, for purposes of illustration, each 120 time setting means as comprising nine contacts 49 corresponding to nine time settings for each feeder. The similar contacts of each set of contacts 49 for each time setting device are connected to common 125 buses 50, 51, 52, 53, 54, 55, 56, 57 and 58, respectively, by means of the conductors 59 and each of the common buses 50 to 58 inclusive are in turn connected by conductors 60 to the contacts 3. The buses 130

50 and 58 inclusive comprise the common time interval buses for the plurality of feeders and correspond to successive time intervals, for instance, any feeder having 5 its trip coil circuit connected to bus 50 will be closed, for instance, in one second and all feeders to be tripped in two seconds will be connected to bus 51 et cetera. The time intervals represented by each bus 50 10 to 58 inclusive is determined by the time required for the switch arm 1 to engage the contacts 3 corresponding to the buses.

To more clearly describe our invention let us assume that feeders 14, 13, 12 and 11 are 15 desired to be tripped in one, two, three and four seconds respectively. The time control means or dial switch for feeder 14 is set by moving the arm 48 to engage the first or one second contact as shown. Trip coil 22 for 20 feeder 14 is therefore connected to bus 50 or the one second bus. The arm 48 of the dial switch for feeder 13 is moved to engage the second contact as shown, which connects the trip coil 21 to bus 51 or the two second bus. 25 In like manner the arms 48 of the dial switches are moved to connect the trip coils 20 and 19 of feeders 12 and 11 respectively to the three and four second buses 52 and 53 respectively.

30 With these time settings for opening the circuits of the various feeders, let us assume an overload occurs on feeder 13, for instance, causing its relay 25 to operate which as before described, starts the motor 7 into operation and closes its contacts 27 and 28 in the circuit of its trip coil 21. The motor 7 rotates the shaft 4 and arm 1 first engages contacts 41 and 42 and, as before, causes the bell alarm 46 to operate. The engagement 35 of arm 1 and contact 41 fails to cause any operation as the trip circuit of feeder 14 connected to bus 50 and contact 41 is open at the contacts 27 and 28 of its relay 26. At the next successive time interval contacts 43 and 44 are engaged and, for the same reasons as just stated, the trip circuit of feeder 13 connected to bus 51 and contact 43 is not closed but the bell alarm 46 is again operated. At 45 the succeeding time interval, which we will assume is three second after initial operation, the contact arm 1 engages contacts 61 and 62 to operate bell alarm 46 and this time a circuit is completed from the positive source of current along conductor 45 to contact ring 6, contact arm 1, contact 61, along its conductor 60, to the three-second bus 52, thence along bus 52, to the conductor 59 corresponding to the time control switch for 50 feeder 12, to contact 63, its contact arm 48 and thence to trip coil 20, through contacts 55 28 and 27 closed by relay 24, to the control bus 31 and back to the negative source of current. Feeder 12 is thereby opened and relay 24 deenergized to open contacts 27 and 60 28 and to simultaneously break engagement

with contact 29 to open the current of motor 7. The contact arm 1 is thereupon returned to initial position as before described.

In like manner, the time required for each feeder to be opened can be determined by the 70 setting of their contact members 48 of their respective time adjusting means and the rotatable switch arm 1 of the main control device operates to close the trip circuit of the feeder in the time desired, that is, at the 75 end of the first time interval, the switch arm 1 of the timing device energizes the first time interval bus 50 and all trip circuits connected to this bus will be operated whose protective relays have assumed circuit closing 80 position. At the end of the second time interval, the second time interval bus 51 will be energized and so on until that bus is energized corresponding to the time setting 85 of the feeder at fault whereupon the feeder 90 is opened and the apparatus returned to normal position. It is thus apparent that we provide a common timing device for all circuits and means whereby the sequence and time of tripping of each feeder may be adjusted at will.

In accordance with the provisions of the patent statutes, we have described the principle of operation of our invention, together with the apparatus which we now consider 95 to represent the best embodiment thereof; but we desire to have it understood that the apparatus shown is only illustrative and that the invention can be carried out by other means.

100 What we claim as new and desire to secure by Letters Patent of the United States, is:—

1. The combination with a plurality of circuits opened at more than one point, 105 means for closing each of said circuits at one point in response to predetermined abnormal conditions, and means in common to all said circuits operative in response to the actuation of any of said first mentioned 110 means for completing those circuits closed by said first mentioned means in certain time intervals.

2. The combination with a plurality of trip circuits open at more than one point, an 115 electroresponsive device for closing each of said circuits at one point in response to predetermined abnormal conditions, and means in common to all said circuits and operative in response to the actuation of any of 120 said electroresponsive devices for completing those circuits closed by said devices in any desired sequence.

3. The combination with a plurality of trip circuits, of control means for said trip 125 circuits comprising an electroresponsive device for each circuit, a device in common to all said circuits, and means for operating said common device in response to the actuation of any of said electroresponsive de- 130

vices, said common device operating as long as any of said electroresponsive devices are actuated to assume a circuit closing position in said trip circuits until that circuit is 5 reached corresponding to the electroresponsive device actuated.

4. The combination with a plurality of circuit opening devices, of feeders controlled by said devices, trip circuits for controlling 10 said circuit opening devices, a first set of contacts in each trip circuit, a second set of contacts in each trip circuit, said trip circuits being operative only upon the closure of both sets of contacts, electroresponsive 15 means for closing the first set of contacts in each trip circuit instantaneously in response to predetermined abnormal conditions in their respective feeders, a common means for closing the second set of contacts 20 in each trip circuit in a certain sequence, and a control circuit for said common means controlled by the actuation of any of said electroresponsive means.

5. The combination with a plurality of 25 electroresponsive devices, separate trip circuits controlled thereby, of a common control means for said trip circuits set into operation by the actuation of any of said electroresponsive devices, including means 30 for moving said control means into circuit closing relation with said trip circuits in successive time intervals, circuit controlling devices operatively related to said trip circuits, each circuit controlling device being 35 actuated only when its respective trip circuit is closed by both its respective electroresponsive device and said common control means.

6. The combination with a plurality of 40 feeders, switches controlling said feeders, trip circuits controlling said switches, electroresponsive devices responsive to conditions on said feeders for controlling said trip circuits, and a common timing means 45 set into operation and controlled by the actuation of any of said electroresponsive devices for completing said trip circuits in a certain sequence.

7. The combination with a plurality of 50 feeders, circuit opening means for said feeders, trip circuits for said circuit opening means, electroresponsive devices actuatable in response to certain conditions on each of said feeders for partially closing said 55 trip circuits, and means operative by the actuation of any of said electroresponsive devices for completing in a certain sequence those trip circuits corresponding to the actuated electroresponsive devices.

8. The combination with a plurality of 60 trip circuits, a plurality of feeders controlled thereby, of relays controlling each circuit in response to predetermined abnormal conditions on their respective feed- 65 ers, and a common means controlled by the

actuation of any of said relays for successively assuming a circuit closing position in said trip circuits until that circuit is reached whose relay is actuated, switches for said feeders adapted to open when their 70 trip circuits are closed by both said common means and their respective relays, and means for returning said common means to its initial position when the feeder at fault is opened. 75

9. The combination with a plurality of feeders, automatic circuit opening devices therefor, and trip circuits for said devices, of means for completing said trip circuits in response to abnormal conditions on their 80 respective feeders in a certain sequence comprising, a device in common to all said trip circuits operative to successively assume a circuit completing position in said trip circuits, separate control means for each trip 85 circuit co-operating with said device and operative to permit said device to complete only those trip circuits corresponding to feeders upon which abnormal conditions exist, and means whereby said device is controlled in response to the actuation of any of said separate control means. 90

10. The combination with a plurality of feeders, circuit opening devices therefor, independent trip circuits for said devices, electroresponsive devices operative to partially close the trip circuits corresponding to feeders upon which abnormal conditions occur, a second device in common to all said trip circuits operative in response to the actuation of any of said electroresponsive devices for completing those circuits partially closed in a certain sequence. 100

11. The combination with a plurality of trip circuits, contacts in said trip circuits, 105 electroresponsive means controlling said contacts of each trip circuit, a device operatively related to all said trip circuits and controlled in response to the actuation of any of said electroresponsive means, second contacts in each of said trip circuits controlled in a certain sequence by said control device, 110 only those trip circuits being rendered operative which have their first mentioned and second contacts both closed at the same time. 115

12. A timing device for a plurality of circuits comprising a first set of contacts operatively related to said circuits, a second set of contacts corresponding with said first set of contacts, a contact member successively engageable with similar contacts in said first and second sets, motive means for causing the engagement of said contact member and each pair of similar contacts in a certain sequence, indicating means actuated by the engagement of said arm and said second set of contacts, the engagement of said contact arm and said first set of contacts acting to control said plurality of circuits. 120

13. A timing device for a plurality of cir- 130

cuits comprising a set of circuit controlling contacts, a similar set of indicating contacts, a coöperating contact member, motive means for causing similar contacts of each of said sets to be simultaneously and successively engaged by said coöperating contact member, means for disconnecting said motive means under predetermined conditions, a resetting means for returning said 10 contact arm to initial position when released from said motive means, and means operative upon the completion by said contact arm of its path of movement for interrupting said motive means and locking said contact arm against its return to initial position.

14. A device for controlling the independent trip circuits for a plurality of feeders comprising a contact member, contacts corresponding to each of said trip circuits, actuating means operative in response to a predetermined abnormal condition on any feeder for producing a relative movement of said contact member and 25 said contacts, said actuating means causing the engagement of said contact member and said contacts to close said trip circuits in a certain sequence, and means in operative relation to each trip circuit for rendering 30 effective the engagement of said contact member and only those contacts corresponding to feeders having abnormal conditions thereon.

15. A device for controlling a plurality of tripping circuits for a plurality of feeders comprising circuit opening devices for each feeder controlled by said trip circuits, relays movable in response to predetermined abnormal conditions on their 40 respective feeders for partially closing their respective trip circuits, a control device operatively related to all said trip circuits, including means for moving said device to complete those circuits partially closed by 45 said relays in a certain sequence.

16. The combination with a plurality of feeders, means controlling the circuits of said feeders comprising a plurality of contacts, a member operative in response to predetermined abnormal conditions on any of 50 said feeders for engaging said contacts in certain time intervals, control circuits for said feeders opened at two points and controlled by the engagement of said contacts, 55 each circuit being closed at one point in response to abnormal conditions on its respective feeder and closed at the other point by the engagement of said member and said contacts, and means for rendering the completion of each circuit in response to the engagement of said member with any of said contacts.

17. The combination with a plurality of trip circuits, electroresponsive devices con-

trolling said trip circuits, a controlling 65 means in common to all said trip circuits operated in response to the actuation of any of said electroresponsive devices to complete said circuits in a certain sequence, and means operatively related to each trip circuit for 70 regulating the sequence of its completion.

18. The combination with a plurality of circuits, separate control means for each circuit operative to assume circuit closing position in its respective circuit in response to 75 predetermined conditions, a common timing device operative upon the actuation of any of said control means to assume a circuit closing position in said circuits in a predetermined sequence, and means whereby the 80 sequence of closing of each circuit can be varied at will.

19. The combination with a plurality of feeders, trip circuits therefor, of electroresponsive means responsive to abnormal conditions on each feeder for partially closing said trip circuits, a common control means set into operation in response to the closure of any of said electroresponsive means for completing said trip circuits in a certain sequence, said electroresponsive means acting 90 to permit the completion of only those trip circuits corresponding to feeders having abnormal conditions thereon, and means associated with said trip circuits for varying 95 their sequence of tripping.

20. The combination with a plurality of conductors adapted to be energized in a certain sequence, a plurality of circuits, electro-responsive means for each circuit operative in response to predetermined abnormal conditions to assume a circuit closing position in its respective circuit, and means for at will connecting each of said circuits to any one of said conductors whereby said 100 circuits are completed in any sequence desired.

21. The combination with a plurality of feeders, independent trip circuits therefor, of electro-responsive means responsive to abnormal conditions on each feeder for controlling said trip circuits, a plurality of conductors successively energized in a certain sequence, time controlling means set into operation in response to the operation of any 110 of the electroresponsive means to energize said conductors, and means for rendering each trip circuit responsive to the energization of any of said conductors, said electroresponsive means operating to permit the 115 closure of only those trip circuits upon which abnormal conditions exist.

22. The combination with a time controlling device comprising a rotatable switch member, contacts adapted to be engaged by 125 the rotation of said switch member in successive time intervals, motive means for automatically rotating said switch member, cir-

cuits operatively related to said contacts, and means controlling each circuit selectively actuatable to set said motive means into operation and to render their respective circuits closable by the engagement of said switch member and their respective contacts.

In witness whereof, the said HEWLETT has

hereunto set his hand this 3rd day of March, 1917; and the said BURKHOLDER has hereunto set his hand this 5th day of March, 10 1917.

EDWARD M. HEWLETT.
CHARLES I. BURKHOLDER.
